FILM DEVELOPING REEL

Albert Drucker, Chicago, Ill., assignor to Burke & James, Inc., Chicago, Ill., a corporation of Illinois

Application August 14, 1942, Serial No. 454,805

10 Claims. (Cl. 242—77)

This invention relates to a portable film developing reel so constructed that a considerable length of film may be readily wound thereon, the convolutions of the coil, which constitutes the body of the reel, being maintained separated from each other so that liquid employed in developing the film may readily contact the face thereof, and which reel, with the film thereon, may be readily transferred from one bath to another.

A further object is to provide in a reel of this character, improved means for anchoring or securing one end of the film to the reel.

A further object is to provide in a reel of this character, a spirally arranged continuous support against which the back of the film rests, and which support is provided with a number of apertures therethrough, not only for the purpose of imparting lightness to the reel, but also to permit the bath solutions to contact and clean substantially the entire area of both faces of the film.

A further object is to provide an improved reel of this character, embodying a spirally wound web or body portion, and arcuate braces secured to one edge of the web for imparting rigidity thereto, to provide maximum support for the web at the periphery of the reel, and improved reel supporting members secured to one of its faces for supporting the reel in the bath and to prevent wear of the body portion of the reel.

To the attainment of these ends, and the accomplishment of other new and useful objects as will appear, the invention consists in the features of novelty in substantially the construction, combination and arrangement of the several parts, hereinafter more fully described and claimed and shown in the accompanying drawing illustrating this invention, and in which—

Fig. 1 is a top plan view of a reel of this character, constructed in accordance with the principles of this invention.

Fig. 2 is a detail sectional view, taken on line 2—2, Fig. 1.

Fig. 3 is a detail perspective view of a portion of the back of the reel, showing one of the braces secured in position, and on an enlarged scale.

The body of the reel consists essentially of a spirally wound web 10 which is constructed of any desired or suitable material, and the strip may be of any desired width and thickness. The web is provided, in its body, with any desired number of apertures 11, and the web is secured at its inner end to a hub 12, the latter consisting preferably of a base plate 13 of annular configuration and having a cross bar or member 14 connected thereto. This hub is preferably in the

form of a spool, having a tubular portion 15 and a cross bar 16 corresponding to the cross bar 14, so that the reel may be mounted upon any suitable support for rotation.

5 The extremity of the inner end of the web 10 is preferably shaped to form a fork or bifurcation 17, to receive the extremity of the film, whereby the film will be anchored to the reel.

Secured across one face of the reel are arcuate braces 18, any desired number of which may be provided, and the backs of the braces are disposed adjacent the hub, while the extremities of the braces are disposed adjacent the periphery of the reel. These braces may be constructed of any suitable material, and are secured in position in any suitable manner, such as by welding or the like. The lateral edges of the braces are preferably cut away, as at 19, for the purpose of lightness.

10 Additional braces 20 of a similar configuration are also secured to the same face of the body of the reel, and a plurality of these additional braces are individual to each of the braces 18, and are disposed within and are substantially parallel with the respective braces 18.

All of the braces extend across the spaces between the convolutions of the coil of the web, and the outer extremity of the coil is anchored, as at 21, to one of the braces.

15 As a means for supporting the reel in the bath and to prevent wearing of the web, suitable supports or projections 22 may be provided, and they may be secured in position by attaching the same to one of the braces or to an arm portion 23 connected to one of the braces. These wearing members or supports are preferably disposed at or near the periphery of the reel, and are preferably constructed of chemically inert materials to prolong their wearing qualities.

20 In use, the free end of the film is inserted in the fork-shaped extremity 17 of the coil, and the coil is then rotated upon a suitable support so as to wind the film upon the web and between the convolutions thereof, the space between adjacent convolutions being somewhat greater than the thickness of the film.

When the film has been wound upon the reel and the reel is placed in a horizontal position, the film will be supported by the braces, and the reel 25 with the film thereon is inserted in the developing or treating baths, and the film is then developed in the usual manner.

With this construction of reel, it will be manifest that it may be lifted from one bath to another while the film is thereon. With the par-

ticular arcuate-shaped braces there will be provided a maximum support for the web at the periphery of the reel, and the braces will impart rigidity. The apertures 11 in the web 10 are provided for the purpose of imparting lightness to the reel, and, at the same time, they will allow the chemical solution to pass to and from the film with the greatest ease.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A film developing reel embodying a spirally wound web, the convolutions of which are spaced a substantial distance from each other, and arcuate braces secured to one edge of said web, said braces curving in directions opposite to the directions of curve of the convolutions of the coil across which they extend.

2. A film developing reel embodying a hub, a spirally wound web encompassing the hub, one end of the web being anchored adjacent the hub, said web being provided with apertures therethrough, a plurality of arcuate braces secured to one edge of said web and extending across the spaces between the convolutions of the coil, the backs of said braces being disposed towards said hub, and the ends thereof, extending towards and anchored at the periphery of the coil, the said braces curving in a direction opposite to the direction of curvature of the convolutions of the coil across which they extend.

3. A film developing reel embodying a hub, a spirally wound web encompassing the hub, one end of the web being anchored adjacent the hub, a plurality of arcuate braces secured to one edge of said web and extending across the spaces between the convolutions of the coil, the backs of said braces being disposed towards said hub, and the ends thereof, extending towards and anchored at the periphery of the coil, and additional arcuate braces individual to each of the first said braces to form groups of braces, said additional braces being disposed within the respective first said braces, the braces of each group being substantially parallel with and spaced from each other.

4. A film developing reel embodying a hub, a spirally wound web encompassing the hub, one end of the web being anchored adjacent the hub, a plurality of arcuate braces secured to one edge of said web and extending across the spaces between the convolutions of the coil, the backs of said braces being disposed, extending towards and anchored at said hub, and the ends thereof towards the periphery of the coil, portions of the sides of said braces being cut away.

5. A film developing reel embodying a spirally wound web, the convolutions of which are spaced a substantial distance from each other, and arcuate braces secured to and supported entirely by one edge of said web, the said braces curving

away from the center of the coil, all of the ends of the braces being disposed adjacent to and anchored at the periphery of the coil.

6. A film developing reel embodying a spirally wound web, the convolutions of which are spaced a substantial distance from each other, and arcuate braces secured to and supported entirely by one edge of said web, the said braces curving away from the center of the coil, all of the ends of the braces being disposed adjacent to and anchored at the periphery of the coil, the lateral edges of the braces being cut away at spaced intervals throughout their length.

7. A film developing reel embodying a spirally wound web, the convolutions of which are spaced a substantial distance from each other, and arcuate braces secured to and supported entirely by one edge of said web, the said braces curving away from the center of the coil, all of the ends of the braces being disposed adjacent to and anchored at the periphery of the coil, the extremities of said ends being deflected against the outer peripheral surface of the coil.

8. A film developing reel embodying a spirally wound web, the convolutions of which are spaced a substantial distance from each other, and arcuate braces secured to and supported entirely by one edge of said web, the said braces curving away from the center of the coil, all of the ends of the braces being disposed adjacent to and anchored at the periphery of the coil, the said braces being arranged in a plurality of groups, the braces of each group being substantially parallel and decreasing in length and curvature from the innermost brace toward the periphery of the coil.

9. A film developing reel embodying a spirally wound web, the convolutions of which are spaced a substantial distance from each other, arcuate braces secured to and supported entirely by one edge of said web, the said braces curving away from the center of the coil, all of the ends of the braces being disposed adjacent to and anchored at the periphery of the coil, the said braces being arranged in a plurality of groups, the braces of each group being substantially parallel and decreasing in length and curvature from the innermost brace toward the periphery of the coil, and a hub to which the inner end of the coil is secured, said hub being disposed intermediate the innermost braces of said groups.

10. A film developing reel embodying a spirally wound web, the convolutions of which are spaced a substantial distance from each other, and arcuate braces secured to and supported entirely by one edge of said web, the said braces curving away from the center of the coil, all of the ends of the braces being disposed adjacent to and anchored at the periphery of the coil, the said braces being arranged in a plurality of groups, the braces of each group being substantially parallel and decreasing in length and curvature from the innermost brace toward the periphery of the coil, the inner end of the coil being shaped to form a seat for one end of a film.

ALBERT DRUCKER.
